UNITED STATES PATENT OFFICE

99,116

DESIGN FOR A RADIANT HEATER

Robert C. Deigert, Toledo, Ohio, assignor to
Harold L. Van Doren, doing business as Harold
Van Doren and Associates

Application February 25, 1936, Serial No. 61,347

Term of patent 7 years

To all whom it may concern:

Be it known that I, Robert C. Deigert, a citizen of the United States and resident of Toledo, in the county of Lucas and State of Ohio, have invented a new, original, and ornamental Design for a Radiant Heater, of which the following is a specification, reference being had to the accompanying drawing, forming a part thereof.

Figure 1 is a perspective view of a radiant heater embodying my design; Fig. 2 is an end elevation thereof, and Fig. 3 is a partial top plan view showing the flaring base.

Each end of the heater presents the same appearance in elevation.

The dominant feature of my design resides in the appearance of the base, without regard to the upright structure shown in dotted lines.

I claim:

The ornamental design for a radiant heater, substantially as shown and described.

In testimony whereof, I have hereunto signed my name to this specification.

ROBERT C. DEIGERT.
